Attorney

UNITED STATES PATENT OFFICE.

OTTO REINHARDT, OF CENTRAL FALLS, RHODE ISLAND.

SHADE AND CURTAIN BRACKET.

Application filed May 16, 1924. Serial No. 713,763.

To all whom it may concern:

Be it known that I, OTTO REINHARDT, a citizen of the United States, residing at Central Falls, in the county of Providence 5 and State of Rhode Island, have invented new and useful Improvements in Shade and Curtain Brackets, of which the following is a specification.

This invention relates to certain new and 10 useful improvements in shade and curtain brackets and the primary object thereof is to provide a simple and economical bracket which can be easily produced and which can also be easily and quickly and also effectively secured to the window frame.

A further object of the invention is to provide a bracket which is reversible and wherein the shade carrier is readily adjustable.

20 A still further object of the invention is to provide a bracket of this type wherein the same is secured to a side edge of the window frame, and wherein such securing means is concealed by the curtain rod support.

The invention has still further and other objects which will be later herein more specifically recited and manifested in the course of the following description.

30 In the drawings:—

Figure 1, is a top plan view of the invention applied in position, the window frame, shade and curtain rods being shown in dotted lines.

35 Figure 2, is a front elevation of the invention in detached position, and

Figures 3 and 4 are sections on line 3—3 and 4—4, of Figure 1, respectively.

In proceeding in accordance with the 40 present invention a base plate or member 1 is employed of substantially T-shape, the shank 2 of which is offset as indicated at 3 so as to dispose the shank from the front face of the window frame when the base is secured thereto. The head 4 is formed with a centrally located and struck-out ear 5, the ear being formed by making parallel slits in the head, with the slits extending through the free outer end edge of the head and then 45 bending the ear to lie at right angles to the plane of the base plate. The ear has a screw or other fastening receiving opening 6 so as to engage the ear to the side edge of the window frame, while the base plate has a similar opening 7 to receive a similar fastening

for securing the base plate to the front face of a window frame.

A slidable and frictionally held shade carrier 8 is mounted on the shank 2 by means of clamping members 9 which embrace opposite sides of the shank, the clamping arms or members being formed integral with the carrier 8 and disposed at right angles to the plane thereof. The clamping arms or members are formed by the ends of a body 60 10, the latter being bowed outwardly at 11 so as to strengthen the body 10.

A plate 12' is secured by bolts 13, in slots 13' formed in the arms 12, of the head 4, the plate 12' being disposed to overlie the 70 opening of the head resultant from the formation of the ear 5. Curtain rod supports 14 are centrally carried by the plate 12' to support rods R for inner and outer draperies or curtains.

75 From the above it will be seen that an exceedingly simple and economical structure is produced, and one wherein the parts are compactly related. The head 4 functions to not only provide the securing ear 5, but also means of support for the curtain rod holder 12'.

The entire structure is bodily reversible so as to enable same to be applied to either side of the window frame, in which regard 85 it will be noted that the curtain rod supports 14, are circular in cross-section and operate in either the position depicted in the drawings or in reversed position.

Having thus described my invention, what 90 I claim as new and desire to secure by Letters Patent is:—

1. In a shade and curtain bracket, a substantially T-shaped base the head of which is provided with a pair of spaced longitudinal arms disposed in substantially the plane of the base and formed to extend beyond the side edge of the window frame, an integral ear on the base disposed between the arms and being perforated and extending rearwardly of the head to form a securing ear which latter is disposed intermediate the inner and outer sides of the head, a curtain rod supporting member disposed over the arms and the space therebetween and concealing the ear, means to secure the member to each of the arms, and a shade carrier connected to the shank of the base.

2. A shade and curtain bracket including 105 a base having spaced arms at one end there-

of disposed in substantially the plane of the base and formed to extend beyond the side edge of the window frame, an integral ear on the base disposed between the arms and 5 extending rearwardly at an angle to form a securing ear which latter is located at a spaced distance inwardly of the outer ends of the arms, a shade carrier on the base, a curtain rod carrier engaged with the arms and disposed over the same and over the space between the arms and concealing the ear, and means to connect the curtain rod carried to the arms.

In testimony whereof I have signed my name to this specification.

OTTO REINHARDT.
